UNITED STATES PATENT OFFICE.

JOHN MACCOLLOM, OF BALLSTON, NEW YORK.

AUTOMATIC CAR-STEP.

SPECIFICATION forming part of Letters Patent No. 487,867, dated December 13, 1892.

Application filed July 23, 1892. Serial No. 440,994. (No model.)

To all whom it may concern:

Be it known that I, JOHN MACCOLLOM, a citizen of the United States, residing at Ballston Spa, in the county of Saratoga and State 5 of New York, have invented certain new and useful Improvements in Automatic Car-Steps; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 This invention relates to an improvement in car-steps; and it consists in a step which may be lowered and which is elevated automatically upon the starting of the train, as will be explained.

20 In the drawings, Figure 1 represents a portion of one end of a car provided with the invention, looking at the rear of the steps. Fig. 2 is an end view of the same, looking at the side of the step. Fig. 3 is a detail perspective view of the hanger which carries the lower step. Fig. 4 is a modification, being a view similar to Fig. 1. Fig. 5 is a detail perspective of the modification.

25 Referring to the drawings, the letter A indicates the car-platform, having at its sides the steps, one set of which is shown at B. This set consists of the usual rigid steps b and a bottom movable step C.

30 Secured to the back b' of the steps b is a guide-frame D, having the inclined guides d d, the space between these guides being dovetailed, as shown. Fitting between these guides d d is the sliding frame E, having the sides e e, which fit in and are adapted to the inclined guides d d. At the bottom this frame 35 E has the outwardly-extended supports e' e', to which is secured the step C. This step, as shown, is wider than the lowest one of the steps b and extends beyond the same, as shown 40 at c.

45 To an eye e² of the frame E is secured one end f of a spring F, the other end f' of which is secured to the car structure. As a part of the frame E there is a barrel G, inside of which 50 is placed a spring g. Entering this barrel and resting against this spring g is a rod H, which passes through guides h in the frame

E and has an end h' extending out beyond one side of said frame. In the guide d, at this side of the frame E, is made a notch d'. Pivoted to the frame E, below the rod H, is a finger K, which is also secured at k to said rod H and has its upper free end k' extending upwardly and inwardly toward the draw-bar L. Secured to this draw-bar L is a striker l, 60 which extends out across and behind the upper end k' of the finger K.

To use this device, the step C is lowered either by pulling on it or by stepping upon it. This pulls down the frame E until the rod H is on a line with the notch d', when the spring g presses the end h' into such notch and locks the frame E down. At the same time the spring F is extended. As soon as the train starts the draw-bar L is elongated, 70 bringing the striker l in contact with the finger K, which bears the rod H back against the spring g. This withdraws the end h' from the notch d', and the spring F, retracting, draws the frame E and step C up.

In Figs. 4 and 5 are shown a modification. Here the construction of the steps and the two frames, the spring, and the lock are the same. Instead of the striker another unlocking mechanism is used. Extending backwardly from the sliding frame E is a flexible arm N, carrying a roller O, which is in the plane of the tread of the car-wheel P. From a wrist-pin o on this roller O a rod R extends toward the frame E and has a slot r, in which 80 is held a headed pin r' on the finger K. When the frame E and step C are up, the roller O is out of contact with the tread of the wheel P; but when the step C and frame E are lowered the roller O is brought in contact with the 85 tread of the wheel P. Now as soon as the car starts, whether forward or backward, the contact of the wheel P with roller, causing the latter to rotate, moves the finger K and unlocks the rod H.

Having thus described my invention, what I claim is—

1. The combination of a movable car-step, a lock for holding such step in its lowest position, and an unlocking mechanism which releases the lock automatically upon the starting of the car, as set forth.

2. The combination of a movable car-step, a spring for lifting it up, a lock for holding such

step in its lowest position, and an unlocking mechanism which releases the lock automatically upon the starting of the car, as set forth.

3. The combination of a movable car-step, a lock for holding such step in its lowest position, and an unlocking mechanism, which communicates with a part of the car structure other than the movable step and releases the lock automatically upon the starting of the car, as set forth.

4. The combination of a movable car-step, a spring for lifting it up, a lock for holding

such step in its lowest position, and an unlocking mechanism which communicates with a part of the car structure other than the movable step and releases the lock automatically upon the starting of the car, as set forth. 15

In testimony whereof I affix my signature in presence of two witnesses.

JOHN MACCOLLOM.
